UNITED STATES PATENT OFFICE.

JOHN LUGER, JR., AND JOSEPH MULLER, OF NORTH ST. PAUL, MINNESOTA; ASSIGNORS, BY DIRECT AND MESNE ASSIGNMENTS, TO EMIL TYDEN, OF HASTINGS, MICHIGAN.

PEDESTAL EXTENSION-TABLE.

SPECIFICATION forming part of Letters Patent No. 741,049, dated October 13, 1903.

Application filed June 17, 1902. Serial No. 112,038. (No model.)

To all whom it may concern:

Be it known that we, JOHN LUGER, Jr., and JOSEPH MULLER, citizens of the United States, residing at North St. Paul, in the 5 county of Ramsey and State of Minnesota, have invented certain new and useful Improvements in Pedestal Extension-Tables; and we do hereby declare the following to be a full, clear, and exact description of the invention, such as will enable others skilled in the art to which it appertains to make and use the same.

Our present invention has for its object to provide an improved means for locking together the sections of so-called "pedestal extension-tables;" and to this end it consists of the novel devices and combinations of devices hereinafter described, and defined in the claims.

20 As is a well-known fact, a serious objection has been raised to the pedestal type of extension-table, due to the fact that the sections of the pedestal as well as the sections of the table-top are liable to separate even when 25 the table is not moved about, and especially when the table is moved from place to place or is turned around or handled in any way.

The invention is illustrated in the accompanying drawings, wherein like characters indicate like parts throughout the several views.

30 Figure 1 is a plan view showing a pedestal extension-table having our improved locking device applied thereto, parts of the table-top being broken away. Fig. 2 is a vertical section taken through the table on the line $x^2 x^2$ of Fig. 1. Fig. 3 is a transverse section on the line $x^3 x^3$ of Fig. 2, some parts being broken away; and Fig. 4 is a view corresponding to Fig. 2, but with parts broken away and with 40 the sections of the table separated.

The numeral 1 indicates the two parts of a table-top, the numeral 2 the two sections of the hollow pedestal, the numeral 3 the extension-slides, and the numeral 4 the center 45 leg. The center leg 4, as is usual, is connected to the intermediate pair of slides 3 and is adapted to be inclosed within the sections of the pedestal 2 when the sections of the table are forced together. The pedestal-

sections 2, as is usual, are provided with 50 feet 5.

One of the pedestal-sections 2 is provided within with a pair of pivoted dogs or latches a , which are pivoted to the opposite sides thereof and when the pedestal-sections are 55 forced together are adapted to engage over pins or projections a' , secured on the inner opposite sides of the other pedestal-sections. When the hooked ends of the dogs a are engaged over the pins or lugs a' , as shown in 60 Figs. 1 and 2, they extend one on each side of the center leg 4. Within the box-like housing afforded by that section of the table-top which moves with the pedestal-section to which the dogs a are pivoted is a vertically- 65 oscillating frame b , pivoted at b' and carrying at its free end a horizontally-extended rod or bar b^2 , the ends of which project for coöperation with cam-strips c , secured on the inner pair of extension-slides 3, as will here- 70 inafter more fully appear.

A pair of light links or rods d connect the intermediate portions of the dogs a to the free end of the oscillating frame b . A pair of springs e , secured at their outer ends to the 75 bottom of one of the box-like table-top sections, engage the rod b^2 at their free ends and yieldingly press the same and said frame b and dogs a upward, as shown in Fig. 4. The springs e may be of wood or metal and may 80 of course take various forms.

With the construction so far described when the table-sections are forced together and as they closely approach the closed position the ends of the rod or bar b^2 are engaged by the 85 cam-strips c , and thereby forced downward, carrying downward also the frame b , links d , and dogs a . Under this movement by the time the sections of the table-top and the sections of the pedestal are forced together the 90 free ends of the dogs a are engaged over the pins or lugs a' , as shown in Fig. 2. When the dogs a and pins or lugs a' are thus engaged, they serve to hold together the sections of the pedestal, and consequently the sections of the 95 table-top; but it is evident that should force be applied tending to separate the sections of the table-top the initial separating move-

ment of the same would release the rod b^2 and frame b , and thereby permit the dogs a to be again raised under the action of the springs e . The dogs a do not, therefore, actually serve as locks, but more properly as latches, which as long as held in engagement with the pins or lugs a' prevent separation of the sections of the table.

To positively hold the latches or dogs a in operative positions, we provide a secondary latch or lock proper, which in its preferred form is constructed as follows:

f indicates an oscillating stop-bracket, which at its upper edge is pivoted within small bearings f' , secured to the top board of that table-top section which carries the oscillating frame b . The free edge or end of the stop-bracket f is mounted for engagement with the bracket b near its free end, and its dimensions are such that it can be thrown straight downward, so as to act as a lock or positive stop to said frame b only when the latter is depressed to its limit, as shown in Figs. 2 and 3, and the dogs or latches a are thrown into operative engagements with the pins or lugs a' .

A sliding bar g is pivoted at its inner end to the free end of the stop-bracket f by means of a short bolt f^2 or other suitable device. At its intermediate portion the bar g is provided with a longitudinal slot g' , in which works a guide-pin g^2 of a bracket g^3 , supported from the overlying table-top section. At its outer end the bar g is preferably provided with a hand-piece g^4 , which is located near one edge of the table-top, so that it may be readily reached.

It is evident that when the sections of the table are forced together, under which movement the frame b is depressed and the dogs or latches a are thrown into operative positions, the stop-bracket or lock b under its own gravity and that of the bar g will tend to fall into its operative position. (Indicated in Fig. 2.) If at any time it should not, it may be positively given such movement by forcing the bar g inward by hand. As is evident, to unlock the sections of the table it is necessary first to draw g outward, so as to turn the lock or secondary latch f into an inoperative position. The locking mechanism above described may be very readily applied to pedestal extension-tables and does not require the cutting either of the sections of the pedestal or the center leg. It is of small cost, is easily operated, and is extremely efficient for the purposes had in view. By actual usage we have demonstrated the efficiency of the device.

It will of course be understood that the device is capable of many modifications in its details of construction. For instance, the sliding bar g may take various forms and might in fact, be in the form of a simple rod. Again, the so-called "lock" pins or lugs a' may take various forms as long as they are adapted for co-operation with latches or dogs of the general character described.

What we claim, and desire to secure by Letters Patent of the United States, is as follows:

1. In an extension-table, the combination with a pedestal made up of two sections, of a lock element within one of the pedestal-sections and a co-operating latch within the other pedestal-section, a latch-actuating connection carried by the same section of the table which carries said latch, and a cam on the other table-section operating on said connection to force the said latch into an operative position when the table-sections are closed together.

2. In an extension-table, the combination with a pedestal made up of two sections, of a center leg embraced by the sections of the said pedestal, a pair of latches pivoted to the opposite sides but within one of the pedestal-sections, a yielding cam-actuated element connected to said pair of latches and carried by the same table-section, a cam movable with the other table-section for action on said cam-actuated element, to force the said pair of latches into operative positions when the table-sections are closed together, which latches extend on opposite sides of said center leg, and lock elements on the other pedestal-section with which said latches engage, substantially as described.

3. The combination with a pedestal extension-table having a pedestal made up of two sections, of a center leg embraced by the sections of said pedestal, a pair of latches pivoted to the opposite sides and within one of the pedestal-sections and working on the opposite sides of said center leg, a pair of projecting lock-lugs secured within and on the opposite side of the other pedestal-section for co-operation with said latches, a spring-pressed frame b pivoted to one of the table-sections and provided with the rods d connecting it to said latches, and cams c carried by the other table-section and operating on a part of said frame b to force said latches into operative positions when the table-sections are forced together, substantially as described.

4. In an extension-table, the combination with a pedestal made up of two sections, of two pairs of latches mounted within said pedestal, one on each side thereof, the co-operating latch elements being carried by different pedestal-sections, a spring-pressed latch-actuating connection carried by the same section of the table which carries the movable elements of the said two latches, a cam carried by one of the sections of the table which has movement in respect to the table-section just noted, and operating on said latch-actuating connection to cause the same to move the movable latch element into operative positions, when the table-sections are moved together, and a lock mounted on the table-section which carries said spring-pressed latch-actuating connection, for action on said connection to hold said latches locked, substantially as described.

5. In a pedestal extension-table, the combination with a hollow pedestal made up of

two sections, of a center leg adapted to be embraced thereby, the laterally-spaced pair of latches *a* pivoted within one of the pedestal-sections and projecting on opposite sides of said center leg when the table is closed up, coöoperating latch elements *a'* secured within the other pedestal - section, the upwardly-spring-pressed lever *b* carried by one of the sections of the table, said frame having the 5 projecting bar *b*², the rods *d* connecting said latches to said frame *b*, the cam-strips *c* carried by the other table-section and operating on the ends of said bar *b*² to force said latches into operative positions when the table-sec- 10 tions are forced together, the pivoted lock *f* 15 overlying said frame *b* and adapted to lock the same in its depressed position and said latches in operative positions, and a sliding rod connected to said lock *f* and terminating at its outer end, near the margin of the table- 20 top, substantially as described.

In testimony whereof we affix our signatures in presence of two witnesses.

JOHN LUGER, JR.
JOSEPH MULLER.
